CLAIM

The ornamental design for a surface ornamentation for a battery charging station, as shown and described.

DESCRIPTION

FIG. 1 is a front elevation view of the battery charging station showing my new design of a surface ornamentation or backlit cutout;

FIG. 2 is a rear elevation view of the charging station;

FIG. 3 is a perspective view thereof;

FIG. 4 is a right side view thereof;

FIG. 5 is a left side view thereof; and,

FIG. 6 is a top view thereof.

The bottom of the battery charging station is unornamented and unclaimed.

The broken lines shown in the drawings are for illustrative purposes only and form no part of the claimed design.
